UNITED STATES PATENT OFFICE.

JOHANNES CRONING, OF HAMBURG, GERMANY.

CYLINDER LOCK.

Application filed July 26, 1920. Serial No. 399,187.

(GRANTED UNDER THE PROVISIONS OF THE ACT OF MARCH 3, 1921, 41 STAT. L., 1313.)

To all whom it may concern:

Be it known that I, JOHANNES CRONING, a subject of the German Republic, and resident of Hamburg, Germany, have invented 5 certain new and useful Improvements in or Relating to Cylinder Locks (for which applications have been filed in Germany March 22, 1919, Patent No. 337,237; in Belgium July 10th, 1920, Patent No. 289,216; in England July 9th, 1920, Patent No. 148,136; in France July 8th, 1920, Patent No. 519,473; and in Switzerland June 26th, 1920, Patent No. 89,383), of which the following is a specification.

15 The object of the invention is to provide a lock of the cylinder type in which the greatest possible simplicity of construction in both the tumbler (or plug) cylinder and the cylindrical case is combined with a minimum of play for the key notches. With this object, the tumbler pins, which are made in one piece as usual and are housed, together with their springs, in the tumbler cylinder, are either slightly off-set or else straight, in 20 which latter event they are provided with a projecting lateral lug to engage with the key, as is well known in connection with cylinder locks having divided tumblers.

Tumbler pins adapted to turn on their 30 own axes must be rounded off spherically at their ends that lie at the line of intersection between the cylinder and cylinder case, in accordance with the curvature determined by the diameter of the cylinder. When the 35 right key is used, the pairs of pins lie, when in the release position, with their contact points in the peripheral surface of the lock cylinder. The contact point of the pairs of pins may, however, lie below the peripheral 40 surface of the lock cylinder by a distance equal to the radius of curvature of the rounded portion, since, on the cylinder being rotated, the upper tumbler pin in that case will only rise instead of lock. Since 45 this radius of curvature is always only a few tenths of a millimetre, all keys that are within this limit and are smaller than the right key, can be used to open the lock.

To obviate this defect, the tumbler pins 50 are prevented, by suitable means or by shaping, from turning on their own axis, so that, in the release position, their end surfaces are flush with the peripheral surface of the lock cylinder.

55 The drawing illustrates several methods

of carrying out the subject of the invention.

Fig. 1 is a vertical section through the lock case and the cylinder. Fig. 2 is a section A—B of Fig. 1,

Fig. 3 shows the tumblers in the set position.

Fig. 4 illustrates a modification.

The cylinder 1 is rotatably mounted in the stationary case 2. In Figs. 1, 2 and 3, each of the tumblers consists of the off-set tumbler pins 3 and the tumbler springs 4. The tumbler pins 3 are adapted to slide axially in two parallel bores and a corresponding recess. Whereas the bore, for example the one on the right, extends entirely through the cylinder, the adjacent hole, in the extension of which the key slot 5 is situated, is not bored entirely through. The under ledge formed by the off-set of the tumbler pin 3, 70 serves to engage with the key and to limit the downward travel of the pin 3. The upper ledge formed by the off-set serves as abutment for the tumbler spring 4. The upper abutment for the spring 4 is formed by a small plate 6, which at the same time acts 75 as a lateral guide for the pin 3.

The modification in Fig. 4 has straight pins 3, the top ends of which are of reduced diameter in order to accommodate the springs 4. An off-set in the form of a lug 85 11, which is firmly secured to the tumbler pin 3 and is adapted to slide in the slot 10 serves to prevent the rotation of the pin and to engage with the key.

The cylindrical lock case 2 is provided 90 with holes 7 and 8 in the line of prolongation of the cylinder bores. Since the tumbler pins 3 are prevented from turning on their axis, their free ends are flush with the peripheral surface of the cylinder when 95 in cylinder release position (Fig. 3). This circumstance determines the total length of each tumbler pin. In the position of repose (Figs. 1, 2 and 4) the upper and lower parts of the tumbler pins 3 are of different 100 heights. They are lifted accordingly by the key, in known manner, to bring them into the release position.

If a tumbler has not been sufficiently lifted one end will remain partly in the bore 8 of 105 the lock case, whereas if one has been lifted too far the other end will project into the bore 7 of the lock case.

Other modifications are also possible. The essential feature of the invention consists 110

in that the straight or slightly off-set tumbler pins are made in one piece and are housed in the tumbler cylinder exclusively, and in that, in order to reduce the play of 5 the key notches to a minimum the tumbler pins are prevented from rotating either by shaping or by the provision of suitable means.

What I claim is:

- 10 1. A lock, comprising a stationary sleeve and a one piece rotatable cylinder therein having transverse bores registerable with perforations in said sleeve at both ends of said bores, spring-urged single-piece straight pins in said bores having an off-set for engagement by a key and capable of entering said perforations and a retaining plate in said cylinder for retaining said pins therein.
- 15 2. A lock comprising a stationary sleeve and a rotatable cylinder therein having transverse bores registerable at both ends with perforations in said sleeve, spring-urged straight one-piece pins in said bores having integral lateral lugs thereon forming off-sets for the engagement of a key and capable of entering the perforations and a plate in said cylinder for retaining said spring-urged pins.
- 20 3. A lock comprising a stationary casing having perforations therethrough on op-

posite sides of a diameter, a rotatable one-piece cylinder in said casing having bores, single piece tumbler pins mounted in said bores, a compression spring for each 35 tumbler, a plate mounted in said cylinder common to said springs to hold the springs and tumblers in the cylinder and a key engaging off-set on each tumbler whereby said tumblers normally engage in one set of perforations on one side of the diameter and engage another set of casing perforations on the opposite side of said diameter when an improper key is used, said tumbler pins with their off-sets being freely inserted in said 40 cylinder when said plate is removed.

4. A lock comprising a stationary casing having perforations therethrough on opposite sides of a diameter, a rotatable cylinder in said casing having straight bores 50 therethrough, a tumbler pin in each bore having a reduced end, a spring on such reduced end, a plate in the cylinder holding said springs and through which said reduced ends pass to engage perforations in the cylinder, the opposite ends of said tumblers being arranged also to engage perforations in the casing.

Signed by me at Hamburg this 1 (first) day of July, 1920.

JOHANNES CRONING.
